UNITED STATES PATENT OFFICE.

THOMAS H. WILLIAMS, OF JERSEY CITY, NEW JERSEY, ASSIGNOR TO THE
A. A. GRIFFING IRON COMPANY, OF SAME PLACE.

DESIGN FOR A RADIATOR.

SPECIFICATION forming part of Design No. 20,780, dated May 26, 1891.

Application filed December 19, 1890. Serial No. 375,210. Term of patent 7 years.

To all whom it may concern:

Be it known that I, THOMAS H. WILLIAMS, a citizen of the United States, residing at Jersey City, in the county of Hudson and State of New Jersey, have invented and produced a new and original Design for Radiators, of which the following is a specification.

The accompanying drawing is a perspective view of a radiator, showing my design.

10 The leading feature of this design consists in a peculiar surface ornamentation of the vertical pipes or loops of the radiator at its top, bottom, and middle in parallel bands, with interposed plain portions parallel with 15 the ornamented portions, the bottom or lower band having the representation of a censer, which is typical of fire. The ornamentation at the upper end of the radiator extends across the top of the vertical pipes, so as to form a 20 cap or crown for the radiator, and the base or legs of the radiator are also ornamented, the ornamentation being continued from the lower ends of the pipes to and upon the legs or base portion. The effect of this ornamentation is to present to view ornamented por-

tions in parallel bands, with contrasting plain portions between the ornamented portions. This effect is pleasing to the eye and relieves the radiator from the unfinished appearance incident to its ornamentation only at the top 30 or bottom thereof.

The particular ornamentation which I have shown in the accompanying drawing consists of a floral design comprising stems, tendrils, and flowers for the upper ends of the vertical 35 pipes and also for the central band. The base portion has also a floral design, and supported thereon is a censer, with the representation of flames emitted from the censer and smoke above the flame. The ends of the radiator 40 are ornamented by geometrical lines, which may be of like or varied configuration upon the various loops.

I claim—

The design for radiators herein shown and 45 described.

THOS. H. WILLIAMS.
